UNITED STATES PATENT OFFICE.

WILLIAM E. NICKERSON, OF CAMBRIDGE, MASSACHUSETTS.

SPEED-REGULATOR FOR ELEVATORS.

SPECIFICATION forming part of Letters Patent No. 399,068, dated March 5, 1889.

Application filed November 30, 1888. Serial No. 292,235. (No model.)

To all whom it may concern:

Be it known that I, WILLIAM E. NICKERSON, of Cambridge, in the county of Middlesex and State of Massachusetts, have invented a new and useful Improvement in Safety - Fluid Speed-Regulators for Elevators, of which the following, taken in connection with the accompanying drawings, is a specification.

The object of my invention is to so construct and arrange the parts of a safety-fluid speed-regulator that all of the movements shall be uniform and steady, avoiding all irregular and abrupt changes either in change of direction or velocity of motion. This object I attain by the mechanism shown in the accompanying drawings, in which—

Figure 1 is an elevation showing such parts of an elevator as are required to illustrate my invention. Fig. 2 is an enlarged plan showing a part of the cap-plate of the main cylinder of my device, the location of the piston-rod and the relief-valves being shown; and Fig. 3 is a cross vertical section taken through the cap-plate on line $x-x$ of Fig. 2 and illustrates the construction and arrangement of the relief-valves.

In that class of safety speed-regulators to which my invention belongs there has been an irregularity of working caused by the fact that there is not so much fluid-space in the cylinder when the piston is down as there is when the piston is up—that is, compensation has not been made for the fluid-space occupied by the piston-rod when the rod is in the cylinder and for the vacancy caused by its withdrawal. This objection has to some extent been obviated in my former inventions, and my present device applies more particularly to that class in which long cylinders are used.

To give additional evenness of motion and security to the device, I have added a valve arrangement adapted to operate in the cap-plate, although the said valve can be placed in the piston and work equally well.

In the drawings, Fig. 1, A represents the carriage of the elevator, B the hoisting-rope, and B' a sheave over which the hoisting-rope B passes.

50 S S' S² is a safety-rope attached to the ele-

vator-carriage, as shown, and, passing up over the sheave D, descends so as to pass under the sheave D', attached to the piston-rod P of the safety device, and then passes upward and is fastened at T. The main cylinder C 55 is made in this case comparatively long, and has in it a loosely-fitting piston, P'. The rod P may also be made to fit loosely, as it is not essential to the working of my device that the parts move without leakage.

60 At the top of the main cylinder C, I have an auxiliary cylinder, C', separated from the main cylinder by the cap-plate E. The auxiliary cylinder is connected to the main cylinder by a passage provided for that purpose, 65 either by means of a pipe, as shown at H H' H², or made in the walls of the cylinders.

The object of having a fluid-passage leading from the auxiliary cylinder C' to the main cylinder C is to admit of the flow of liquid 70 from one side of the piston P to the other in its movement in the cylinder, as well as to admit of the flow of the excess of fluid that would be in the cylinder C when the piston is down, and the piston-rod is within it.

75 If the pipe H' H H² were omitted, then on the upward movement of the piston and consequent withdrawal of the piston-rod a vacuum would be formed underneath the piston, as no oil could get down during the upward 80 stroke, the pressure being upward and against it. This vacuum is the cause of more or less unevenness and uncertainty of motion in stopping and starting the car.

85 It is to be understood that the flow of fluid from one side of the piston to the other as it moves in the cylinder C is partially provided for by leakage about the piston or by orifices made in it.

In the cap-plate E, I have valves of peculiar construction, as shown in Figs. 2 and 3. The valve V has an upward-projecting stem, V', upon which I place adjusting-weights W. The valve has also a downward-projecting stem, V³. The two stems V' and V³ serve to 95 keep the valve in place and leave it free to move up and down, or, in other words, close and open as the piston rises or lowers. The valve works in a chamber, R, formed in the cap-plate E, as shown in Fig. 3. The chamber 100

R has a series of openings, P P, toward the auxiliary chamber C', and a corresponding series, P' P', toward the main cylinder C. V², Fig. 3, is a screw-bushing inserted in the under side of the cap-plate E, to complete the chamber R and to afford a guide for the valve-stem V³, as well as a rest or stop for the shoulder V⁴ of the valve-stem V³. The number of the valves V and the series of openings P P and P' P' may be varied to suit the requirements of the case. The valve V opens downwardly to admit the free passage of the liquid from the auxiliary cylinder C' to the cylinder C and closes only upwardly.

15 By weighting the valve V, I am enabled to so balance it that it will close at any desired upward pressure of the fluid in the cylinder C, this pressure depending upon the velocity of ascent of the piston P', which has a definite ratio to the descent of the elevator-carriage A. Thus by varying the weight W, I can control or fix the maximum velocity of descent of the elevator-carriage.

20 I claim—

1. In a fluid speed-regulator for elevators, 25 the combination of the safety-rope S S' S², the piston-rod P, and piston P', with the cylinder C, cap-plate E, valves V, auxiliary cylinder C', and pipe H' H H², leading from the auxiliary cylinder C' to the lower part of the cylinder 30 C, all operating together substantially as described, and for the purpose set forth.

2. In a safety-fluid speed-regulator for elevators, the combination of the piston-rod P, 35 piston P', main cylinder C, cap-plate E, and valve V, having adjusting-weights W, with the auxiliary cylinder C' and pipe H' H H², substantially as described, and for the purpose set forth.

In testimony whereof I have signed my name 40 to this specification, in the presence of two subscribing witnesses, on this 28th day of November, A. D. 1888.

WILLIAM E. NICKERSON.
